UNITED STATES PATENT OFFICE.

JOSEPH R. JAMES, OF SILVER CITY, MISSISSIPPI.

MONUMENT-BASE.

1,363,511.

Specification of Letters Patent. Patented Dec. 28, 1920.

Application filed February 17, 1920. Serial No. 359,393.

To all whom it may concern:

Be it known that I, JOSEPH R. JAMES, a citizen of the United States, residing at Silver City, in the county of Yazoo, State of Mississippi, have invented certain new and useful Improvements in Monument-Bases; and I do hereby declare the following to be a full, clear, and exact description of the invention, such as will enable others skilled in the art to which it appertains to make and use the same.

This invention relates to metallic structures such as are usually employed as the bases for poles and posts, and its object is to produce a base which is designed to be anchored adjacent a grave, and means for fastening upon it an upstanding so-called tombstone of any appropriate material and of various sizes within limits.

One feature of the invention consists in the structure of the base so that a wooden slab or panel can be employed as the tombstone, and it will be held above and out of contact with the ground and therefore remote from the deteriorating effects of moisture.

Another feature of the invention lies in the fact that, while its structure is such that it can be cast, it affords provision for the ready engagement with it of fasteners spaced at various points so that slabs of different sizes can be mounted upon the base.

Other objects will appear in the following specification and claims, and reference is made to the drawings wherein:

Figure 1 is a perspective view of a grave at whose head is placed a base of this kind supporting a slab of wood, this view showing a bolt for attaching the fasteners to its sides and a screw for holding the fastener to its nearest edge.

Fig. 2 is a vertical section through the center of the base and slab of Fig. 1.

Fig. 3 is a top plan view and Fig. 4 a bottom plan view of the base.

Fig. 5 is a detail of one of the fasteners.

While it is true that this device might be made of such size that it could support a monument—especially if a number of these bases were used—its general purpose is to support a tombstone or more particularly a headstone or a footstone. Yet these so-called "stones" are often of other material than stone, and the slab 1 shown in Fig. 1 might be of wood into which the inscription could be cut, and the whole coated with a

very durable paint or enamel. Such a structure would resist the deteriorating effects of the weather for years, but the toughest paint yields in time to the influence of moisture at 60 or below the earth's surface, and I have therefore devised a base for supporting the slab above said surface. This base I preferably make of metal, and it may be formed in any appropriate way, possibly by molding or casting it in one piece. If it be of a metal which will rust, it may be subsequently treated as by being painted, japanned, enameled, or galvanized, so that it also will resist the deteriorating effects of 70 climate and contact with the earth. For a footstone the base and the slab would both be smaller but for a headstone the base could well be from one to two feet long, about a quarter as wide as it is long, and as thick 75 as thought necessary. It is substantially rectangular, and its upper face 2 is flat as seen in Fig. 3. Its lower face 3 is provided with a longitudinal channel 4 and a transverse channel 5 crossing the same at the center, and the body of the base is cut through with slots 6 in the channels 4 and 7 in the channels 5, the inner ends of the slots 7 being quite close to each other and the inner ends of the slots 6 somewhat remote. Long pins or spurs 8 depend rigidly 80 from the ends of this base, and instead of casting the same as integral parts of the body structure, they might be made as separate elements and attached later by any suitable means.

Fasteners are employed for attaching the slab to the base, and each is of the construction best seen in Fig. 5, and preferably also made of metal suitably treated to prevent 95 rust. It has a flat body 10 pierced with two or more holes 11, the body being thickened a little at its lower end into a foot 12, a stem 13 which is of a size to pass through and turn in one of said slots; and at the lower end of the stem a T-head 14 which stands substantially in the plane of the body. Four of these fasteners are provided with each base, and the whole can be manufactured and sold to the person who desires to 100 erect a headstone or footstone adjacent the grave of a departed friend or relative.

In the use of this device, the ground is leveled off at the point where the monument or tombstone is to stand, the base is brought into position and its spurs forced 110 down into the ground until its lower face

3 rests thereon or is perhaps pressed thereinto, as preferred. In fact, it is quite possible to dig out a little cavity in the ground and pour into it a plastic such as cement, 5 and then put the base into position and bear it down until its lower face is pressed into the cement and the latter rises a little into the channels 4 and 5. In any case, a slab 1 rectangular in cross section is next brought 10 into position and set up upon the upper face 2 of the base, exactly where it is desired that it shall stand. The four fasteners are now brought into use, each having its T-head 14 passed down through one of 15 the slots and turned across the same so that its body 10 can be laid flat against the face or edge of the slab and its foot 12 will rest on the upper face 2 of the base at opposite sides of the slot. Finally the fasteners 20 are attached to the slab by means of bolts, screws, nails, or keys 15 which are passed through appropriate holes 11 and into registering holes formed into the slab itself. If the latter is of stone or composition or of 25 metal or wood properly treated or coated, it will last for years as above stated and it will be supported by this base and the fastening devices in a strictly upright position rather than becoming decayed or injured by moisture above and below the earth's surface, 30 and blown over or tilted by the winds and storms. If the slab be of wood, I consider it desirable to have a considerable portion of the base stand well above the level of the 35 earth, and therefore when it rains the water will run off on the base rather than standing beneath the wooden slab where it might any time affect the paint on the lower end. It will be obvious that a device of this 40 character renders it possible for the poorest families to put up a headstone in memory of a dear one, even though the slab or "stone" be of wood rather than of some more expensive material usually employed for this 45 purpose. Also it will be obvious that this device may be used to advantage when stone or other heavy material is employed, because in any case it supports the slab in upright position.

50 What is claimed as new is:

1. The combination with a board; of a

base provided with longitudinal and transverse slots, fasteners having narrow stems with T-heads at their lower ends flattened for passage through said slots and flat bodies at their upper ends, and means for securing said bodies to the faces and edges respectively of said board to hold the T-heads across said slots.

2. The combination with a base having 60 a slot through it, and a headboard on the base partly overlapping its slot; of a fastener having a flat body attached to one face of the headboard, a thickened foot resting upon the base, a stem below the foot passing 65 through the slot, and a T-head at the lower end of the stem held across such slot by the attachment of the fastener to the headboard.

3. The herein described base for monuments and the like, the same comprising a body having a flat upper face and a channel in its lower face and slots through the base opening into said channel, combined with fastening devices having T-heads at their 70 lower ends whereby they may be inserted through said slots and turned to connect them with the base and then slid in the 75 slots until they contact with the monument, and means for attaching their upper ends 80 to said monument.

4. In a device of the class described, the combination with a substantially rectangular base flat on its upper face and having longitudinal and transverse channels in its 85 lower face intersecting each other, the body being provided with slots through it opening into said channels; of a set of fasteners each having a flat body for attachment to an article mounted on said base, a 90 stem at the lower end of its flat body and of a size to pass through one of said slots, and a T-head at the lower end of the stem and standing in the same plane as the body of the fastener.

In testimony whereof, I affix my signature, in the presence of two witnesses.

JOSEPH R. JAMES.
